BUFFING OR POLISHING MACHINE

Carl O. Johnson, Springville, N. Y., assignor to
Ralph B. Waite, Springville, N. Y.

Application May 27, 1936, Serial No. 82,103

5 Claims. (Cl. 51—84)

This invention relates to machines for buffing and polishing cutlery and the like.

More particularly the invention is concerned with improved means for reciprocating the work 5 relative to the polishing roll.

The invention together with its objects and advantages will be best understood from a study of the following description taken in connection with the accompanying drawings wherein:—

10 Figure 1 is a front elevational view of the machine with certain parts removed.

Figure 2 is a transverse sectional view taken substantially on the line 2—2 of Figure 1.

15 Figure 3 is a detail plan view of the work holder.

Figure 4 is a front elevational view of the work holder.

Figure 5 is a transverse sectional view taken substantially on the line 5—5 of Figure 3.

20 Figure 6 is a fragmentary plan view showing a valve actuating mechanism and associated parts and

25 Figure 7 is a view partly in section and partly in elevation showing the valve and actuating means therefor.

Referring to the drawings by reference numerals, the machine comprises generally a table 1 supported by legs or standards 2.

30 Rising from the table 1 are upright bearing members 3 and said bearing members 3 support therebetween a rocker shaft 4 to which are splined or otherwise secured arms 5 and 6. Supported by the arms 5 and 6 is a polishing roll 7, the shaft of which is journaled in the free ends 35 of the arms 5 and 6.

35 Arm 6 is extended, as best shown in Figure 1, to form a bracket to which an electric motor 8 is secured, the shaft of the motor forming an extension of, or being directly connected to, the shaft 9 of the roll 7.

40 Similarly the shaft 10 of a second and lower roll 11 is journaled in the free ends of arms 12 and 13 splined or otherwise secured to a rocker shaft 14 mounted below shaft 4 in the bearing 45 members 3. Arm 12 is extended to form a bracket to which an electric motor 15 is secured, the shaft of motor 15 forming an extension of, or being directly connected to, shaft 10 of roll 11. Thus each roll 7 and 11 is independently driven 50 by its motor and directly from its motor.

55 Shafts 4 and 14 are adapted to be simultaneously rocked in opposite directions by means of a turn buckle 16, the oppositely threaded portions of which engage in nuts 17 and 18 pivoted respectively in the free ends of arms 19 and 20

which are splined respectively to shafts 4 and 14. As shown in Figure 2 shafts 4 and 14 are geared together as by segmental gears 21 and 22 respectively secured to said shafts so that rotation of turn buckle 16 will result in simultaneously rocking the shafts 4 and 14 in equal amounts but in opposite directions, thus swinging the rolls 2 and 3 toward or from each other to adjust their spacing for work of different thickness.

Secured transversely to the top 1 are fixed guides 23 formed on one side with ribs that are received in ways 24 provided at respective opposite end edges of a slide 25. Slide 25 is thus mounted on the top 1 for reciprocation transversely with respect to the axis of the rollers 7 and 11 and for reciprocating the slide 25 there is suitably mounted beneath the top 1 a cylinder 26 in which operates a piston the rod 27 of which is suitably secured to a bracket 28 depending 20 from one end of the slide 25 as best shown in Figures 1 and 2.

For reciprocating the piston within the cylinder 26 there is suitably mounted on the extended part 29 of arm 12 which forms the bracket for 25 the motor 15 a liquid pump 30 which is driven from the motor 15 through the medium of a belt and drive means 31. Pump 30 serves to draw liquid from a liquid chamber 32 provided in one of the stands 2 through a pipe 33 that leads 30 from the chamber 32 to the intake side of the pump. From the outlet side of the pump there extends piping 34 which is connected with one side of the casing of a valve assembly 36. Valve assembly 36 has one side thereof connected 35 through the medium of piping 37 with one end of piston 26 while the other side of the casing of valve 36 is connected in a similar manner with the relatively opposite end of the cylinder 26 so that liquid under pressure will first be supplied to one end of cylinder 26 for moving the piston therein in one direction, and then into the cylinder 26 at the opposite end thereof for moving the piston in a reverse direction for reciprocating the slide 25. For bleeding the ends 40 of the cylinder in alternation and for directing the liquid exhausting from the ends of the cylinders back to the chamber 34 there is provided a return pipe connection 38 between the valve 36 and the chamber 32.

Also for bypassing the liquid from the pump back to the chamber 32 before the liquid reaches the valve 36 there is provided a suitable by-path pipe connection 39 between pipe 34 and chamber 32 equipped with a valve 40.

55

For operating the valve 37 in a manner to control the operation of the piston within the cylinder 36 for reciprocating the slide 25 the crank 41 of the stem of valve 37 has a pin and slot connection 42 with a lever 43 which is pivoted at one end as at 44.

Suitably mounted on one side of the slide 25 are bearings 45 in which is journaled the respective opposite ends of a shaft 46 that at one end is equipped with a hand wheel 47 and threads 48 cooperable with a fixed nut 49 on an adjacent bracket 45 so that as the hand wheel 47 is rotated in a proper direction the shaft 46 may be fed for passing the free end thereof into the other of the bearings 45 or said shaft may be retracted for withdrawing the shaft axially through the bearings 45.

Shaft or rod 46 is provided with two series of relatively spaced openings 51 through the medium 20 of which and pins 52 top blocks 50 are secured at the desired relative adjustment on the rod 46. The blocks 50 are arranged so as to engage the lever 43 in alternation incidental to a reciprocation of the slide 25 to thereby operate the valve 25 37 in a manner to control the supply of liquid under pressure to cylinder 26 for reciprocating the piston in said cylinder.

For normally holding the valve 37 in a neutral position there is provided a spring 53 which at 30 one end is secured at the connection 42 between the valve crank 41 and lever 43 and which at its opposite end is provided to engage in a selected notch of a series of notches provided in the up-standing flange of a plate 54 suitably secured to 35 the top of the slide 25. (See Figures 6 and 7.)

On the top thereof the slide 25 is provided with apertured lugs 55 arranged in pairs and having a sliding fit within the apertures of each pair of lugs 55 is a rod 56. Rods 56 extend transversely 40 to the line of movement of the slide 25 and secured to the respective opposite ends of the respective rods 56 are lugs 57 provided on the under-side of a slide 58 which reciprocates relative to the slide 25 and in a path parallel to the rollers 7 45 and 11 or at right angles to the path of travel of the slide 25.

For reciprocating the slide 58 there is provided on the table 1 and extending from one edge thereof a bracket 59 to which is secured an electric motor 60. Suitably connected with the shaft of the motor 60 through the medium of reduction gearing arranged within a gear case 61 mounted on one side of the casing of the motor 60 is an eccentric 62 to which is connected one end of a pitman rod 63 that in turn is pivotally connected as at 64 with a bracket arm 65 that is secured to one of the lugs 57 as shown in Figure 1.

Secured to and rising from the slide 58 are standards 66 to the upper edges of which are 60 pivoted as at 67, and as shown in Figure 4, channel members 68. For securing the members 68 at the desired angular adjustment relative to the upper edges of the standards 66 are adjusting screws 69.

Bolted or otherwise secured as at 70 to the members 68 are plates 71 on which rest the respective opposite ends of a work holding bar 72 disposed there-between, and the bar 72 is supported for sliding movement laterally toward or 70 away from the rolls 7 and 11.

For guiding the bar 72 as it is adjusted relative to the rolls there are provided guide arms 73 that extend from a member 74 that is disposed between and connects the free ends of the members 68. At one edge thereof the work holding

bar 72 is provided with a depending skirt 74 provided with slots to accommodate the guide arms 73. Also extending from the skirt 74 are handle extensions 75 which are used to facilitate the sliding of the work holding plates 72 toward or 5 away from the rolls.

To maintain the respective opposite end edges of the bar 72 in sliding contact with the plates 71 there are secured by bolts or the like 77 spring clips 78 that have portions overlying the plates 71 10 and the adjacent ends of the work holding plate 72 as clearly shown in Figures 3 and 4 and also in Figure 5.

Adjacent the free edge thereof the work holding plate 72 has a plurality of pins 79 projecting 15 upwardly therefrom to engage in the usual rivet openings provided in the handle ends of knife blades 80.

For retaining said ends of the blades 80 engaged with the pins 79 there is provided an apertured 20 clamping bar 81 the apertures of which accommodate the upper ends of the pins 79. For retaining the bar 81 in clamping position relative to the plate 72 to confine the handle ends of the knives 80 on the pins 79 there are provided a 25 pair of spring fingers 82 which have ends yieldably urged into engagement with the bar 81 through the medium of screws 83 and springs 84 disposed about the screws between the clamping fingers 82 and the plate 72. 30

Also the clamping fingers 82 have portions resting on angular brackets 84 suitably mounted on the flange 76 of plate 72 and which brackets have upstanding ends upon which intermediate portions of the clamping fingers 82 rest so that by 35 screwing home the screws 83 said fingers 82 will be placed under tension for securely retaining the clamping plate 81 in position.

From the above it will be seen that by adjusting the members 68 angularly with respect to the 40 upper edges of the standards 66 the blades 80 may be properly positioned in the bight or space between the rotating rolls 7 and 11 to insure proper contact of the rolls with the knife blades to insure thorough polishing of the blades on 45 both sides thereof. It will also be seen in this connection that by properly adjusting the angular position of the members 68 the blades may be so positioned as to contact with but one roll to polish or buff a single surface of each knife blade. 50

As is thought apparent from the foregoing, the knife blades or other work carried by the work support will be reciprocated in the bite of the rotating rolls 7 and 11 by the reciprocation of slide 25, and that simultaneous reciprocation 55 parallel to the rolls is imparted to the work by slide 58.

It is thought that a clear understanding of the invention, its operation and utility will be apparent to those skilled in the art without a more 60 detailed description.

Having thus described the invention what is claimed as new is:—

1. In a buffing and polishing machine, a table, a pair of rolls mounted on the table, means connected to the shaft of each roll to drive it independently of the other, means connected with the rolls for adjusting their spacing to various thicknesses of work, a slide mounted on the table for reciprocation transversely to the axis of the 65 rolls, a second slide mounted on the first slide for reciprocation parallel to the axis of the rolls, a work support carried by the second slide, hydraulic means connected with the first slide for reciprocating it, an electric motor mounted on 70 75

the table, and an operating connection between said motor and the second slide for reciprocating the latter.

2. A buffing and polishing machine comprising a table, a pair of rolls mounted on the table, means connected to the shaft of each roll for driving it independently of the other, means connected with the rolls for adjusting the same toward or away from each other for adjusting their spacing to various thicknesses of work, a slide mounted on the table for reciprocation transverse to the axis of the rolls, hydraulic means connected with said slide for reciprocating it, a second slide mounted on the first slide for reciprocation parallel to the axes of the rolls, a motor mounted on the table, means operatively connecting the motor with the second slide for reciprocating it, and a work support mounted on the second slide including a pair of standards rising from the second slide, members pivoted to the upper ends of the standards, means engaged with said members and the standards for securing said members at the desired angular adjustment relative to the upper edges of said standards, a work holding plate supported between said members for sliding movement thereon toward and away from the rolls, resilient spring devices on said members and yieldably engaging the work holding plate for securing the latter at the desired adjustment, and means on the work holding plate for clamping the work thereto whereby the work may be held in the space between the rolls for contact with both rolls or in contact with a selected one of the rolls, optionally.

3. A buffing and polishing machine comprising a pair of buffing and polishing rolls, means connected with the rolls for driving them, a work support, a slide connected with the work support and mounted for reciprocation parallel to the axes of the rolls, a second slide beneath the first slide and mounted for reciprocation transversely to the axes of the rolls, and hydraulic means for reciprocating the last named slide including a cylinder, a piston mounted for reciprocation in the cylinder and having a rod connected with the last named slide for transmitting movement of the piston to the slide, means for controlling the supply of liquid to the respective opposite ends of the cylinder including a valve, and means connected with the valve and the last named slide for operating the valve in response to the reciprocating movement of the last named slide.

4. A buffing and polishing machine comprising a pair of buffing and polishing rolls, means connected with the rolls for driving them, a work support, a slide connected with the work support and mounted for reciprocation parallel to the axes of the rolls, a second slide beneath the first slide and mounted for reciprocation transversely to the axes of the rolls, and hydraulic means for reciprocating the last named slide including a cylinder, a piston mounted for reciprocation in the cylinder and having a rod connected with the last named slide for transmitting movement of the piston to the slide, means for controlling the supply of liquid to the respective opposite ends of the cylinder including a valve, and means connected with the valve and the last named slide for operating the valve in response to the reciprocating movement of the last named slide, a prime mover, and means operatively connecting the prime mover with the first named slide for reciprocating the latter.

5. A buffing and polishing machine comprising a pair of buffing and polishing rolls, means to drive said rolls, a slide mounted for reciprocation transversely to the axes of the rolls, a second slide mounted on the first slide for reciprocation parallel to the axes of the rolls, a work support carried by the second slide, and means for reciprocating the slides simultaneously including hydraulic means connected with the first slide and characterized by a control valve arranged adjacent to the first slide and means on said valve and on the first slide for actuating the valve as the slide approaches the limit of its movement in either direction.

CARL O. JOHNSON. 45
